United States Patent

Des. 235,322
Patented June 10, 1975

235,322

BICYCLE RACK

Robert E. Sill, 429 15th Ave. SW.,
Rochester, Minn. 55901

Filed Oct. 26, 1973, Ser. No. 409,952

Term of patent 14 years

Int. Cl. D8—99

U.S. Cl. D12—115

FIG. 1

FIG. 2

FIG. 1 is a perspective view of a bicycle rack showing my new design; and

FIG. 2 is a top plan view thereof with the top and bottom supports partially broken away for convenience of illustration.

I claim:

The ornamental design for a bicycle rack, as shown.
